UNITED STATES PATENT OFFICE

2,433,101

DEVICE FOR STRETCHING THE SELVEDGE
THREADS ON LOOMS

Raymond Dewas, Amiens, France

Application May 18, 1945, Serial No. 594,487
In France December 29, 1944

6 Claims. (Cl. 139—97)

1

This invention chiefly relates to looms and more particularly to looms having a continuous weft supply and in which the weft, supplied by large fixed bobbins, is inserted into the shed by means of inserting members having no cop.

In the manufacture of cloth fabric, a tightly woven edge, or selvage is formed on each side of the material to prevent the warp threads of the material itself from unraveling until it is used. Present methods for controlling the tension of the warp threads have been generally unsatisfactory because one or more of the threads may slacken, in the course of weaving, and cause defects to occur in the fabric.

Present methods for adjusting the tension of warp threads for the selvage such as the provision of breaking means for the bobbins or the grouping of the threads in a suitable hook and weight assembly, have proven unsatisfactory because, in the first instance it was difficult to obtain uniform tension on all the threads, and in the second instance they became seriously entangled.

The object of this invention is to remedy the aforementioned difficulties by the employment of a device that will provide uniform tension for all of the warp threads of the selvage and in addition will prevent the entanglement thereof.

According to one form of the invention a heavy container, having an open top and adapted to receive weights of various sizes is provided with a series of spaced openings near the top edge of two parallel sides. The selvage threads are looped, first thru the series of holes in one side, then over a fixed support and lastly thru the holes on the remaining side. By this procedure, the selvage threads remain separated to avoid tangling, and the box travels downwardly as the slack, produced by keeping the threads constantly under tension, is accumulated.

Another form of the invention comprises the employment of thread guides before and after the weighing device to separate the threads before being looped thru the holes in the weighing device and then to reassemble the threads before they take their place beside the warp threads forming the fabric itself.

It should be noted that in normal weaving operations, the warp threads forming the fabric itself are not subjected to the great degree of tension required of the selvage threads.

The characteristic features of this invention will be better understood in the course of the following description when taken in connection with the accompanying drawings, by way of example only, of preferred embodiments of the inventive idea.

In said drawings, which relate to a stretching device for one of the selvedges:

Fig. 1 is an elevational end view of the warp beam showing the manner in which the selvedge

2

threads behind the loom are submitted to the action of the stretching device.

Fig. 2 is an elevational front view of the heavy weighting container suspended to the selvedge threads.

Fig. 3 is a sectional view of said container through the line 3—3 of Fig. 2.

Fig. 4 is a view similar to Fig. 2 showing a modification of the container.

10 Fig. 5 is a front elevational view of the pre-separating guide.

Fig. 6 is a plan view of said preseparating guide seen from above.

Fig. 7 is a front elevational view of the re-assembling guide, of which

Fig. 8 is a plan view, seen from above.

Fig. 9 is a front elevational view of another form of a container, of which

Fig. 10 is an end view.

20 In said figures, 1 is the roller or beam from which the warp threads 2 are unwound which, after their passage on a first bar 4, pass round a second bar 5 where the warp sheet is separated and divided into two parts of which one, 2a, comprises the selvedge threads which are looped through the stretching or weighting device, while the other, 2b, comprises all the other warp threads going directly to the backrest 6 and then to the droppers 7 of the warp stop motion where

30 the selvedge threads 2a take their place back again, side by side with them, all warp passing then through the healds. (not shown).

The stretching device comprises a U-shaped container formed, for instance, of a folded metal sheet, the sides 8a and 8b of which are provided in their upper part with opening formed holes 9 suitably spaced from one another and through each of which passes one of the selvedge threads

40 2a (the number of which is supposed to be eight in the example shown). The bottom of the basket is provided with cut out parts 8c which are turned up and on which the desired number of adjusting weights 10 is fitted (Fig. 1). As shown in the drawing, the side 8a can be lightened by being provided with an opening 20 for compensating the slight pivoting effect resulting from the passage of the threads through the basket.

In combination with the container 8, the device 50 comprises rods 11, 12 and 13 secured on a support fast with the frame of the loom, said threads passing round the rod 11 and going down in order to pass through the holes 9 of the side 8a of the container, whereafter they move upward again

55 in order to pass on the rod 12, go down again and pass through the holes 9 on the side of 8b of the container and move upward again, pass on the rod 13 and go to the warp stop motion droppers 7 and from the latter to the healds. This zigzag travel of the threads 2a makes it possible to ac-

60

commode a greater length of thread and to provide more uniform tension.

Before the container 8, the device can comprise a preseparating guide formed of a small bar 14 provided with holes 15 through which the threads pass, said bar being advantageously carried by an arm 14a ending in a socket 16 mounted on the rod 11.

Near the outlet, the device comprises a reassembling guide 17 provided with a notch 18 for recollecting the threads 2a in order to unite them in a group again, said guide being advantageously carried by an arm 17a ending in a socket 19 mounted on the rod 11, preferably on the side opposed, with respect to the selvedge threads passing round said rod, to that which is occupied by the socket 16. Since the bar 14 and the guide 17 are secured on the rod 11 by means of their sockets 16 and 19 respectively, it is possible to obtain all the required positions.

The device being formed in this manner, it is apparent that, as the weaving operation progresses elongation of the selvedge threads because of the tension under which they are placed is compensated by the progressive downward travel of the container 8. As soon as the container 8 comes near the ground, the work-woman stops the loom, seizes the selvedge threads 2a in that part between the reed and the fell of the cloth and pulls on them in order to raise the basket again. She then cuts the excess of length of the threads which have been thus pulled, making a knot in front of the fell of the cloth and starts the loom again.

Of course, the invention is by no way limited to the particular form described since it is possible to modify the details and also use equivalent means without departing from the scope and spirit of the invention.

For instance, in order to avoid the necessity of threading in the threads, the holes 9 provided in the sides of the container 8 may be advantageously replaced by notches 21, as shown in Figure 4; in this case, the small guide bar 14 is also provided with notches.

In order to facilitate the shifting of the threads, the holes 9 or the notches 21 of the container 8 can be provided with rounded parts; likewise the rods 11, 12 and 13 can be substituted by rollers freely rotating about fixed axes on one of which the sockets 16 and 19 are wedged.

The rods, 11, 12 and 13 can be formed of channeled rollers, each channel receiving a selvedge thread.

If desired, the rod 11 can be replaced by the small guide 14.

Instead of a single container one can provide a plurality of containers arranged side by side and/or parallel to one another, as for instance a container for each travel of the selvedge threads.

The double travel of the selvedge threads through the heavy container can be substituted by a simple travel or by a triple travel, said container, can offer the most varied forms and be formed either of a folded metal sheet, as shown, or of a shaped rod, or of an assembly of flat or

sectional irons, or by a moulded piece of plastic material and the like.

It can also be formed of channeled rollers 22, as shown in Figures 9 and 10, mounted on a common support 23 and provided with one or more spindles 24 for receiving the weights 10; said rollers can also be independent of one another. Said container formed of rollers can itself receive the most varied forms.

10 I claim:

1. A device for stretching selvedge threads, principally on looms and more particularly on looms provided with a continuous supply of the weft through large fixed bobbins, the weft thread being inserted by means of inserting members having no cop, said device comprising a container adapted to receive weights of various sizes, and openings in said container through which said selvedge threads pass to suspend said container whereby the said threads are maintained under uniform tensions and spaced from one another.

2. A device for stretching selvedge threads comprising a container, and openings in said container spaced from one another and through each of which passes one of the selvedge threads in order to insure the suspension of the said container which is arranged to receive removable masses for modifying its weight.

3. A device according to claim 1 wherein the container comprises one or more rollers provided with channels each of which is engaged by one of the selvedge threads.

4. A stretching device according to claim 1, comprising, in combination with the container, reversing guides which permit of tackling the selvedge threads so as to impose on them a zigzag travel during which they pass several times through the said container.

5. A device according to claim 1, comprising in combination with the container, a reassembling guide arranged behind said container on the travel of the selvedge threads whereby the said threads are brought closer to one another before they take their place back again by the side of the other warp threads.

6. A device according to claim 1, comprising, in combination with the container, a preseparating guide arranged before said container and adapted for spacing the selvedge threads from one another before they pass through the said container.

RAYMOND DEWAS.
